(57) **CLAIM**

The ornamental design for a nylon sling adjusting device, as shown and described.

DESCRIPTION

FIG. 1 is a top perspective view of the nylon sling adjusting device of the claimed invention;

FIG. 2 is a front view thereof;

FIG. 3 is a bottom view thereof;

FIG. 4 is a side view thereof;

FIG. 5 is a rear view thereof; and,

FIG. 6 is a side view thereof.

The elements shown by broken lines are for illustration purposes only and form no part of the claimed design.
